PROTECTIVE DEVICE

Emil Kolisch, New York, N. Y., assignor to Continental Silver Co., Inc., Brooklyn, N. Y., a corporation of New York

Application August 18, 1948, Serial No. 44,845

24 Claims. (Cl. 219—44)

1

This invention relates to protective devices, more especially for electrical appliances of the type used in the home or in the offices of physicians and dentists and particularly to a device which breaks the circuit when the appliance is overheated and may be readily reset to operativeness and, though applicable to heaters for water, liquids or fluids generally, such as for sterilization or for culinary purposes, is shown herein applied to a coffee percolator.

It is among the objects of the invention to provide a protective device for an electrical heating appliance of the above type which device is of simple, relatively inexpensive, compact and rugged construction, which functions with a minimum number of operating parts none of which is delicate or apt to become out of order, which device does not detract from the normal operation of the appliance, which is not exposed to contact with the materials to be heated by the appliance and which yet may be completely concealed from the exterior of the appliance, which functions without appreciable arcing both in maintaining the circuit in use and in interrupting the circuit upon overheating as for instance in the absence of desired liquid therein, and which admits of being instantly, unerringly and automatically, restored to operativeness by resort to a simple control manipulation on the part of the unskilled user such as by the turn of a knob accessible from the exterior of the appliance and without the need for any disassembly tools or for reaching into the interior of the device.

It is another object of the invention to provide a multiple fusible link protective device of the above type by which a uniformly effective electrical contact with respect to one of the fusible links is assured even in the absence of close tolerances in manufacture or assembly, by which the break of the circuit upon softening of such fusible link under excessive heat is sharply and automatically effected by a snap action and by which the connection of a fresh fusible link is effected by automatically snapping such fresh link into place under the manual control of the user.

It is a feature of the invention to provide a plurality of fusible links of which one only is maintained in operative position where it is subjected to the heat evolved in the appliance, the remaining fusible links being in reserve for ready replacement upon fusing and rupture of the link in use under excessive heat. To this end the fusible link in action is in engagement with a

2

stop or contact in effective heat conducting and circuit closing relationship with the heating element of the appliance. Spring drive means, resiliently arrested by the engagement of the link and stop are effective to break through the link by a snap action upon softening of the latter by overheating, thereby to break the circuit. The circuit is restored at will by manual control to effect engagement of the next link with the stop.

19 In a preferred embodiment the links are carried on a movable, preferably a rotary mount and the stop is rigidly and immovably mounted to arrest said mount which is under the sustained influence of a stressed resilient drive, effective to snap through the link when it softens and propel the mount in direction to bring the next link into resilient arresting engagement with the immovable stop. Releasable means is provided preferably in the form of a pawl functioning upon rupture of a link to arrest the spring driven mount before the next link reaches the immovable stop, thereby to assure that the circuit remains open until the releasable means has been displaced as by manually turning a knob accessible from the bottom of the device.

In a preferred construction, the fusible links radiate from a rotatable mount which desirably rises from the bottom of the device and stressed resilient means are provided associated with the mount to urge the latter to rotate in one direction, while the immovable stop is affixed above the links in the path of movement thereof. A releasable pawl is preferably provided, coacting with the rotatable mount to retain the links thereon spaced from said stop after the fusible link in action has ruptured, thereby ensuring that the circuit will remain open, and a trigger is provided controlled by said knob to actuate 30 said releasable pawl to enable said mount to rotate under the urging of said stressed resilient means to bring the next link into engagement with said stop, so that positive electric contact is made to close the circuit.

45 This application is a continuation in part of my co-pending applications Serial No. 767,696 filed August 9, 1947 and Serial No. 24,233 filed April 30, 1948.

In the accompanying drawings in which are shown one or more of various possible embodiments of the several features of the invention,

Fig. 1 is a longitudinal cross-sectional view of the electrical appliance with parts broken away,

Fig. 2 is a transverse cross-sectional view taken along line 2—2 of Fig. 1,

Fig. 3 is a fragmentary longitudinal cross-sectional view taken along line 3-3 of Fig. 1.

Fig. 4 is a fragmentary transverse cross-sectional view taken along line 4-4 of Fig. 1.

Fig. 5 shows a fragmentary plan view of the mount after a link has ruptured.

Fig. 6 is a fragmentary bottom view of the appliance taken along line 6-6 of Fig. 1.

Fig. 7 is a bottom plan view of the heater housing.

Fig. 8 is a fragmentary perspective view of the device showing one of the link mounts, and

Fig. 9 is a fragmentary longitudinal cross-sectional view of another embodiment of the device.

Referring now to the drawings there is shown a preferred embodiment of the protective device as applied to a coffee percolator 10. The latter comprises a container 11 affixed as by welding as at 12, to a hollow base 13 which has an annular flange 14 at the bottom thereof affixed to the bottom rim 15 of the base as by rivets 16. A bottom plate 17 is affixed to said flange 14 by means of screws 18 which also mount legs 19 and which pass through the bottom plate 17 and are threaded into corresponding openings 21 in the flange 14.

Carried by the top 25 of the base 13 and extending through an opening 26 therein is a generally cylindrical, preferably ceramic mount 27. A cylindrical protective housing 28 encompasses the main length of the mount which protrudes above top 25 and has an inturned rim 29 extending under diametrically opposed laterally extending ears 31 integral with the mount 27. To permit assembly of the housing 28 to the mount, the rim 29 may have diametrically opposed slots 32 to accommodate said ears 31 so that upon slight rotation of the housing 28, after introduction of the ears into the slots 32, the housing is attached relative to the mount. A nut 33 secured upon the threaded base 34 of the mount 27 causes the ears 31 to be pressed against the inturned rim 29 of the housing, rigidly to clamp the housing and the mount to the base.

A high resistance wire 35 is wound around the main length 36 of the mount 27 which is of slightly reduced diameter forming an annular ledge 37. One end 38 of the wire is connected to the head of a bolt 39 which extends through a bore 41 in the ledge 37 and the base 34 of the mount 27, and protrudes from the bottom of the mount as at 42, being retained therein by a nut 43. The other end 44 of the resistance wire 35 passes through a bore 45 in the ledge 37 and base 34 and extends from the bottom of the mount as at 46 and is connected by a lead 47 to a terminal plug 48 rigidly affixed to the wall of the base 13 and insulated therefrom by insulating washers 49, as is the companion terminal plug 51.

The protective device disposed within the hollow base 13 establishes an electric circuit from the two ends 38 and 44 of the heating coil to the two terminals 48 and 51, respectively. The device includes a plurality of fusible links 54, each carried by a corresponding support 55. An electrical contact closes circuit to one only of said links. The rupture of the fusible link under excessive heat results in automatic interruption of the electric circuit, preferably under release of stress resiliently imposed. The contact and the fusible links are then relatively displaceable so that upon manual trigger action the circuit is automatically snapped closed with another link in operative position. It is, of course, not neces-

sary that the entire length of the link be of fusible material but only a portion thereof need be in order to break the circuit when such fusible portion ruptures.

The embodiment of the protective device herein chosen to illustrate my invention comprises a substantially L-shaped bracket 56 of heat conducting material such as sheet metal having its transverse arm 58 extending at substantially right angles to downwardly extending stop or contact finger 59, and affixed to the bottom end 42 of bolt 39 by nut 43, as shown in Fig. 3.

Mounted within the base 13 on the upper face 71 of a substantially circular flat domed portion 72 formed in the bottom plate 17, is a substantially U-shaped bracket 74, having laterally extending arms 75 which are affixed to face 71 by rivets 76. Extending through an opening 77 (see Fig. 3), in the cross piece 78 of bracket 74, and through an axial opening 79 in the face 71 of the bottom plate 17, is a shaft 81 having a flange 82 integral therewith and seated on the cross piece 78. A collar 83 is affixed on shaft 81 beneath cross piece 78 by a set screw 84 securely, yet rotatably to support the shaft on bracket 74.

The lower end of shaft 81 extending through opening 79 has a crown cap 69 affixed thereon by set screw 70, the cap having a pointer on the periphery thereof which coacts with a dial face 73 to indicate the setting of the shaft.

Carried on the shaft 81 is a mount 80 comprising a disc 85 of insulating material mounted at its axis on the upper part 86 of shaft 81, as is a generally circular metal contact plate 87 positioned on said disc 85 and which has a hub 88 of insulating material through which said upper part 86 extends.

Plate 87 has a plurality of radiating slots 90 therethrough, illustratively six in number, through each of which extend the arms 89 of the substantially L-shaped bracket or support 55, base 92 of which extends at right angles to arms 89 and is sandwiched between disc 85 and plate 87, and in electrical contact with the latter. By means of a nut 93 threaded on the end 86 of shaft 81, the plate and disc are tightly clamped together against flange 82, thereby rigidly clamping the bases 92 of supports 55 therebetween, securely to retain arms 89 in upright position.

The upper ends of each pair of arms 89 are bent over a fusible link 54 securely to hold the latter parallel to and radially of the plate 87 and aligned with the contact finger 59, so that when the mount is rotated in the manner hereinafter described, the links will successively abut thereagainst.

A tensed coil spring 63 is provided, encompassing shaft 81 between collar 83 and face 71 of bottom plate 17. One end 64 of coil spring 63 is positioned in a transverse slot 65 in shaft 81 and the other end 66 of the coil spring is secured to a bolt 67 held in place on cross piece 78 by nut 68, thereby normally urging shaft 81 and the mount 80 to rotate in a counterclockwise direction.

In order to limit the rotation of mount 80 an L-shaped bracket 98 is provided also affixed on face 71, the upstanding arm 99 of which has affixed thereto an insulating block 101, the latter carries a laterally extending contact arm 102 affixed thereon by screws 103 electrically connected by lead 107 to terminal 51. Arm 102 is of spring metal resiliently urged for electrical contact at its free inturned or toe end 104 with the rim of contact plate 87. Contact plate 87 is provided with a plurality of ratchet teeth or

notches 105 illustratively six in number aligned respectively with the radiating links 54, which notches coat with the end 104 of contact arm 102, end 104 functioning as a ratchet pawl to prevent rotation of the mount in a counterclockwise direction under the action of coil spring 63.

In order to provide a convenient means for releasing the pawl 104 so that the mount 80 may rotate under the urging of coil spring 63, to place the next link into operation, means are provided comprising an upright shaft 57 positioned in a hub 60 rigid with the face 71. The lower end of shaft 57 which extends through opening 81 in the bottom plate has a knob 95 affixed thereto by set screw 96 and the upper end of shaft 57 which extends above hub 60 has a threaded opening therein, and a substantially triangular trigger 62 of insulating material is retained on said upper end by a screw 50 which passes through an opening in said trigger into the threaded opening in said shaft 57.

The trigger 62 is so positioned with respect to resilient arm 102 that when knob 95 is turned an apex 52 of the trigger will abut against the arm 102 to cam the latter outwardly away from notch 105 in plate 81 thereby enabling the tensed coil spring 63 to rotate the mount and the links therein.

The legs 19 of the base and the dome 12 afford ample clearance for the knob 95 and the cap 69 when the appliance 10 is placed on a table.

In operation, with a link 54 against stop 59, as shown in Fig. 2, pawl 104 will be against the smooth portion 106 of the rim of plate 81 between two successive notches 105 and hence only the abutment of link 54 and stop 59 restricts the rotation of mount 80 under the stress of wound spring 63. The container 11 is filled with liquid and a source of current is applied to terminal plugs 48 and 51. The circuit is from terminal plug 48, lead 47, heating element 35, bolt 39, bracket 56, stop 59, link 54, support 55, metal carrier plate 87, contact arm 102 and lead 107 to terminal 51. Since a good heat conducting path is established from the source of heat to the stop finger 59, overheating (as for instance in the absence of liquid) will cause the engaged link 54 to soften. Before the fusible link melts, its mechanical strength will have been so greatly reduced that the tension of the stressed coil spring 63 which is urging mount 80 in a counterclockwise direction will force the link against stop 59 with such pressure that the link will quickly be sheared as mount 80 rotates under the urging of coil spring 63 thereby breaking the circuit so rapidly that there is no danger of arcing, and the mount will rotate until pawl 104 abuts against the succeeding notch 105 at which point stop 59 will be spaced from the succeeding link 54.

But for this mechanical shearing action, if the user should cut off the electric current when the fusible link had just begun to soften and had been deformed from its original shape, it would remain in this deformed condition when the apparatus was permitted to cool to normal temperature. The deformity of the link might cause only slight contact to be made between the link and the stop finger 59, resulting in a high resistance joint which, upon passage of current therethrough upon further use of the appliance, might cause sufficient heat to develop at the point of contact to melt the link even though the container was full of water and the appliance operating normally.

As the links other than the one in operation,

are not in contact with any heat conducting metal such as the stop 59, although the temperature in the base will rise due to overheating in container 11, this rise will not be sufficient to weaken them before the circuit is broken by the rupture of the link in operative position.

The user, noticing that the device is not operating, will turn knob 95 to again complete the heating circuit. As the link that formerly had been against stop finger 59 has been sheared, there is nothing to impede the counterclockwise rotation of the mount 80 to bring the next link 54 against stop 59 except the notch 105 in which pawl 104 is positioned, however when the knob 95 is turned in either a clockwise or counterclockwise direction, an apex 52 of trigger 62 will press against the arm 102 to cam the latter outwardly to remove pawl 104 from the notch, whereupon tensed coil spring 63 will quickly rotate the mount until the next link abuts against stop 59. The user will have a ready indication that a new link is in circuit by reason of the fact that cap 69 will rotate with shaft 57 to indicate the next number on the dial 13. It is to be noted that as coil spring 63 is in highly tensed condition the link will exert considerable pressure against the stop finger thereby ensuring that a positive contact will be made between the link 54 and the stop finger 63 that will not jar loose.

Thus by the device hereinabove described, an efficient protective device is provided that will positively break the circuit in the event of any overheating, yet can quickly and simply be adjusted to restore the appliance to operative condition without the need for special skill or any tools.

Were the fusible link engaging stop spring hinged and the rotary fusible link mount to be manually propelled for placing in circuit the next link after a fusible link had been ruptured by the action of such stop, tolerances would be required in the manufacture and assembly of the parts. The effectiveness of the fuse link rupturing and fuse link engaging action would depend on the operator rather than on a spring drive and the operating would accordingly not be as uniformly dependable.

When all the fusible links have been melted, it is a relatively simple matter to remove the bottom plate 17 by unloosening screws 18. The entire carrier unit or mount 80 can then be replaced by a new unit or the plate 81 can be removed from disc 85 by removing nut 93 whereupon the link carrying supports can be withdrawn from slots 90 and replaced.

The embodiment hereinabove described is for use with a percolator of metal having a relatively high melting point, such as aluminum in which the soldered joints also have such a high melting point and consequently a rapid transfer of heat to the fusible links is not required. However where metal having a lower melting point, such as chromium is used, it is necessary that the links be heated sufficiently to rupture long before the metal of the receptacle or the solder used melts. To this end, as shown in Fig. 9, a substantially L-shaped bracket 56' of heat conducting material such as sheet metal is provided, the transverse arm 58' of which has an opening 100 therein through which the threaded portion 34' of the ceramic mount extends, the arm 58' of the bracket being securely clamped against the interface of top 25' of the base by nut 33'.

The downwardly extending arm 111 of the bracket has affixed thereto the upper end 112

of stop or contact finger 59' the lower end 113 of which is in the path of movement of the fusible links. In order electrically to insulate the stop finger 59' from the bracket 56' yet provide for effective heat transfer therebetween, a mica insulating strip 114 is positioned between arm 111 and end 112 of the stop finger, the character of mica being such as to provide an effective electrical insulation yet permit rapid transfer of heat. To retain the stop finger and mica strip against arm 111, aligned openings 115 are provided through the arm 111, mica strip 114 and end 112. A centering grommet 116 of insulating material is positioned in each of the openings in end 112 and by means of a rivet 117 which extends through grommet 116, mica strip 114 and arm 111, the aforementioned elements are rigidly clamped together.

In order to provide an electric path from the heating element to the stop finger 59' a connecting strip 118 is provided, one end 119 of which is affixed to the stop finger by rivet 121 and the other end 122 of which has an opening therethrough through which end 42' of bolt 39' extends, the end being secured on said bolt by nut 43'.

As the arm 58' of bracket 56' is in close proximity to the top 25' of the base and to the heating element it is readily apparent that if any excessive heat should develop, this heat would quickly be transmitted through the stop or contact finger 59' to fusible link 54' and cause the latter to soften and thereupon rupture to break the circuit. It is also readily apparent that such heat transfer could occur more quickly with the above construction than when the bracket 56 is connected only to end 42 of bolt 39 as in Fig. 1 which is spaced some distance from top 25 and the heating element.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A protective device for electric heating appliances, said device comprising a mount having a plurality of fusible links radially arranged thereon, a contact stop of heat conducting material in the substantially circular path of said links engaged by one of said links and effecting circuit closure through said mount, means upon softening of the engaged link to rupture the latter, thereby to disengage said link from said contact stop and break the circuit, and means to effect relative movement of the stop and the next fusible link for engagement thereof.

2. A protective device for electric heating appliances, said device comprising a mount having a plurality of supports thereon, a fusible link carried by each of said supports and extending radially of said mount, a contact stop of heat conducting material in the substantially circular path of said links engaged by one of said links and maintaining the corresponding support in circuit, means upon softening of the engaged link to rupture the latter, thereby to disengage said link from said contact stop and break the circuit, and means after rupture of the engaged link to effect relative movement of the contact

stop and the next fusible link for engagement thereof.

3. A protective device for electric heating appliances, said device comprising a mount having a plurality of supports thereon, a fusible link carried by each of said supports and extending radially of said mount, a contact stop of heat conducting material engaged by one of said links and maintaining the corresponding support in circuit, means to maintain a pressure at substantially right angles against the engaged link whereby upon weakening of the said link, the contact stop will rupture the latter to break the circuit, and means after rupture of said engaged link to bring the next fusible link into engagement with said contact stop.

4. The combination set forth in claim 3 in which said last named means are resilient and normally urge said mount to rotate in one direction.

5. The combination set forth in claim 4, in which means are provided coacting with said mount to limit the rotation thereof.

6. A protective device for electric heating appliances, said device comprising a mount having a plurality of supports thereon, a fusible link carried by each of said supports and extending radially of said mount, a contact stop engaged by one of said links and maintaining the corresponding support in circuit, means to maintain a pressure of the engaged link against the contact stop, whereby upon weakening of said link, the contact stop will rupture the latter to break the circuit, and manually controlled means after rupture of said engaged link automatically to bring the next fusible link into engagement with said contact stop.

7. In an electrical device of the type having a heating element; the combination therewith of a rotatable insulating disc, a generally circular metal contact plate rigid with said disc and having a plurality of radiating slots therein, a plurality of brackets clamped between said disc and said plate and extending respectively through said slots, a fusible link at the extending end of each of said brackets, a contact finger of heat conducting metal in electrical circuit with said heating element and in the path of rotation of said fusible links, and means to rotate said disc and said plate, thereby successively to bring each of said links into contact with said contact finger.

8. The combination set forth in claim 7, in which means are provided, resiliently urged against the rim of said metal plate to make contact therewith.

9. A re-settable protective device for electric heating appliances, said device comprising a rotatable mount, a plurality of supports rigid with said mount, a fusible link carried by each of said supports and extending radially of said mount, a contact finger of heat conducting material engaged by one of said links and maintaining the corresponding support in circuit, stressed resilient means normally urging said mount to rotate in one direction and forcing said link against said finger whereby upon weakening of the engaged link, the stressed mount will rotate to rupture said link, thereby to open the circuit.

10. The combination set forth in claim 9 in which means are provided to retain said circuit in open condition after said link has ruptured.

11. In an electrical appliance of the type having a base, a bottom plate, a heating element affixed to the top of said base and terminal plugs

for connecting a source of current to said heating element; the combination therewith of a protective device therefor, said device comprising an insulating disc rotatably mounted on said bottom plate, a generally circular contact making element rigid with said disc and rotatable therewith, a plurality of brackets rigid with said disc and contact element and rising therefrom, a fusible link affixed to the free end of each of said brackets a contact finger electrically connected to one end said heating element and depending from the top of said base in the path of movement of said fusible links, and a contact arm electrically connected at one end to one of said plugs and having its free end resiliently urged against the rim of said contact element to make contact therewith.

12. In an electrical appliance of the type comprising a base, a bottom plate affixed thereto, a heating element affixed to the top of said base and terminal plugs for connecting a source of current to said heating element; the combination therewith of a protective device therefor, said device comprising an insulating disc, a generally circular contact making plate affixed to said disc and having a plurality of radiating slots therein, a shaft rigid with said disc and passing through said bottom plate for rotatably mounting said disc and said contact plate, a resilient arm on said bottom plate coacting at one end with said contact plate to limit the rotation thereof and electrically connected at the other end to one of said terminal plugs, a plurality of substantially L-shaped brackets clamped between said disc and said contact plate and respectively rising upwardly through the slots in said contact plate, a fusible link affixed to the free end of each of said brackets, and a contact finger connected to one end of said heating element and depending from the top of said base in the path of movement of said fusible links successively to engage the latter as said disc and said carrier are rotated.

13. The combination set forth in claim 12, in which said contact plate has a plurality of ratchet teeth on the rim thereof and said resilient arm has a pawl at the end thereof adapted to engage said ratchet teeth to limit the rotation of said contact plate.

14. The combination set forth in claim 12, in which resilient means are provided coacting with said shaft normally urging the latter with its disc and contact plate to rotate in one direction.

15. A resettable protective device for electric heating appliances, said device comprising a rotatable insulating disc, a plate affixed to said disc, a plurality of radially positioned supports rigid with said plate and said disc and rotatable therewith, a fusible link carried by each of said supports, a contact finger of heat conducting material in the path of rotation of said links, engaged by one of said links and maintaining the corresponding support in circuit, stressed resilient means urging said disc to rotate and forcing said link against said finger, whereby upon weakening of the engaged link, the latter will be ruptured, means effective upon such rupture to retain said contact finger spaced from the next link, and means effective upon release of the latter means to bring said next link into engagement with said contact finger.

16. A resettable protective device for electric heating appliances, said device comprising a rotatable insulating disc, a generally circular contact making element affixed to said disc, a plurality of supports rigid with said element and

said disc and rotatable therewith, a fusible link at the end of each of said supports, a contact of heat conducting material in the path of movement of said links, engaged by one of said links and maintaining the corresponding support in circuit, stressed resilient means normally urging said mount to rotate in one direction and forcing said last named link against said contact whereby, upon weakening of the engaged link, the stressed mount will rotate to rupture said link, thereby to open the circuit, means coacting with said contact making element to limit the rotation of said mount and maintain said circuit in open condition, and means coacting with said last named means to permit further rotation of said mount to bring the next link into engagement with said contact and close said circuit.

17. In an electrical device of the type having a heating element; the combination therewith of a rotatable insulating disc, a generally circular metal contact plate rigid with said disc and having a plurality of radiating slots therein, a plurality of metal brackets clamped between said disc and said plate and extending respectively through said slots, a fusible link at the extending end of each of said brackets, a contact finger of heat conducting metal in electrical circuit with said heating element and in the path of rotation of said fusible links, means resiliently urged against the rim of said plate to make contact therewith, stressed resilient means to rotate said disc and said plate, thereby successively to bring each of said links into contact with said contact finger, whereby upon weakening of the engaged link the latter will be ruptured, thereby to break the circuit, and releasable means to limit the rotation of said disc and said plate.

18. A resettable protective device for electric heating appliances, said device comprising a rotatable mount including an insulating disc, a generally circular contact making element superposed thereon, means rigidly clamping said contact element and said disc together, fuse link carrying elements rising from said contact element, a fusible link at the end of each of said carrying elements, a contact of heat conducting material engaged by one of said links pressing thereagainst and maintaining the corresponding carrying elements in circuit, whereby upon weakening of the engaged link the latter will be ruptured, means successively to bring said links into engagement with said contact, said rotatable mount having peripheral ratchet teeth and coacting pawl means for limiting the rotation of said mount.

19. In an electrical appliance of the type comprising a base, a bottom plate affixed thereto, a heating element and terminal plugs for connecting a source of current to said heating element; the combination therewith of a substantially cylindrical insulating mount affixed to the top of said base, extending through an opening therein, and supporting said heating element, a substantially cylindrical casing affixed to said base and encompassing said heating element, a bolt extending through an opening in said mount, said bolt being connected at its upper end to one end of said heating element and protruding from said mount at its lower end, a substantially L-shaped bracket, the transverse arm of which has an opening therein through which the lower end of said insulating mount extends, said arm being clamped to the underside of the top of said base, a contact finger rigidly affixed to the vertical arm of said bracket, extending substantially longitudinally thereof, electrically insulated

therefrom and in heat conducting relation thereto, an electrical conducting connecting strip affixed at one end to said contact finger and at its other end to the protruding end of said bolt, a mount having a plurality of supports therein, a fusible link carried by each of said supports, one of said links being engaged by said contact finger and maintaining the corresponding support in circuit, means upon softening of the engaged link to rupture the latter, thereby to disengage said link from said contact finger and break the circuit, and means after rupture of the engaged link to effect relative movement of said finger and the next fusible link for engagement thereof.

20. In an electrical appliance of the type comprising a base, a bottom plate affixed thereto, a heating element affixed to the top of said base and terminal plugs for connecting a source of current to said heating element; the combination therewith of a protective device therefor, said device comprising an insulating disc, a generally circular contact making plate affixed to said disc and having a plurality of radiating slots therein, said contact plate having a plurality of notches on the rim thereof substantially aligned with said radiating slots, a shaft rigid with said disc and passing through said bottom plate for rotatably mounting said disc and contact plate, resilient means coacting with said shaft normally urging the latter with its disc and contact plate to rotate in one direction, a resilient arm on said bottom plate having a pawl at one end thereof adapted successively to engage said notches to limit the rotation of said contact plate, and electrically connected at its other end to one of said terminal plugs, manually operated trigger means to disengage said pawl from its respective notch, a plurality of substantially L-shaped brackets clamped between said disc and said contact plate and respectively rising upwardly through the slots in said contact plate, a fusible link affixed to the free end of each of said brackets, a contact finger connected to one end of said heating element and depending from the top of said base in the path of movement of said fusible link normally spaced therefrom when said pawl is in one of said notches, and engaged by the next link when said trigger is operated.

21. The combination set forth in claim 20, in which said resilient means to rotate said shaft

comprises a wound coil spring encompassing said shaft, affixed thereto at one end and rigidly affixed at its other end to said base.

22. The combination set forth in claim 20, in which the end of said shaft passing through said bottom plate has means thereon to indicate the setting of said shaft and said disc and contact plate thereon.

23. The combination set forth in claim 20, in which said trigger comprises an insulated cam member normally in engagement with said resilient arm, a rotatable shaft supporting said cam member at its upper end and passing through said bottom plate, and a knob affixed to the lower end of said shaft, whereby when said knob is turned, said insulated member will cam said resilient arm outwardly to withdraw said pawl from said notch, thereby permitting rotation of said shaft by said resilient means therefor.

24. A protective device for electric heating appliances, said device comprising a rotatable mount having a plurality of radiating fusible links thereon, a contact finger of heat conducting material in the path of rotation of said fusible links and normally engaging one of said links to effect circuit closure through said mount, tension spring drive means urging said mount to rotate in one direction the latter being resiliently arrested by the engagement of said link and said contact whereby upon weakening of the engaged link the stressed mount will rotate to rupture said link, thereby to open the circuit, means automatically to limit the rotation of said mount to retain said contact spaced from the next fusible link, and means effective upon release of the latter means to bring said next link into engagement with said contact finger.

EMIL KOLISCH.
